Primary Examiner — John Windmuller*Assistant Examiner* — Steven J Czyz(74) *Attorney, Agent, or Firm* — Lowe Graham Jones PLLC(57) **CLAIM**

We claim the ornamental design for a hand strap, as shown and described.

DESCRIPTION

FIG. 1 is a top perspective view of a hand strap, showing our new design.

FIG. 2 is a right side view of the hand strap.

FIG. 3 is a front view of the hand strap, the rear view being a mirror image.

FIG. 4 is a top view of the hand strap.

FIG. 5 is a bottom view of the hand strap.

FIG. 6 is a left side view of the hand strap; and,

FIG. 7 is a top perspective view of the hand strap, shown with environment.

The broken lines depict portions of the article and environment that form no part of the claimed design.
